UNITED STATES PATENT OFFICE.

HOWARD F. SNYDER, OF NEWTON, IOWA, ASSIGNOR TO THE MAYTAG COMPANY, OF NEWTON, IOWA, A CORPORATION OF IOWA.

DRAINING DEVICE.

1,271,625.

Specification of Letters Patent.

Patented July 9, 1918.

Application filed November 14, 1914. Serial No. 872,083.

To all whom it may concern:

Be it known that I, HOWARD F. SNYDER, a citizen of the United States, residing at Newton, in the county of Jasper and State of Iowa, have invented a new and useful Improvement in Draining Devices, of which the following is a specification.

My invention relates to a draining device, and particularly to a draining device for wash tubs such as used in washing machines or the like.

It is an object of my invention to provide a valve or draining device for wash tubs or the like which is of simple construction and easy of manipulation.

It is another object of my invention to provide a valve of the kind described susceptible of instant control so that it may be opened or closed instantly.

It is another object of my invention to provide a valve or draining device which may be locked in open position but when so locked may be instantly released.

Other objects and advantages of the invention will appear as the description to follow proceeds:

In the drawing Figure 1 is a sectional view of my device shown as applied to a washing machine tub, a fragment of which is shown in section.

Fig. 2 is an end elevation of my device.

Fig. 3 is a cross-sectional view on the line 3—3 of Fig. 1.

Fig. 4 is a perspective view of a portion 35 of the valve stem and the handle of my device.

In the drawing 1 represents in general the bottom of a wash tub which is provided with an aperture 2 through which the water 40 may be drained.

The fixture of my invention comprises a tubular portion 3, at right angles to which is an enlarged valve chamber 4 from which the discharge 5' projects downwardly. A 45 closure such as 5 is screwed into the valve chamber 4, as shown in the drawings. The upper end of the tubular portion 3 fits tightly into the aperture 2 in the tub and is preferably provided with a notch such as 50 6 to firmly engage the wood. A flange 7 is made integral with the tubular portion 3 and of oblong form to accommodate the bolts 8 by which the device is clamped to the bottom of the tub, a gasket 9 being interposed between the flange and the bottom

of the tub to seal the joint. At the junction of the enlarged valve chamber 4 with the tubular portion 3 of the device I provide a cylindrical seat in which is seated the washer 10 having therein an aperture 11 60 which is concentric and flush with the aperture 12 between the tubular member 3 and the valve chamber 4. The closure 5, screwed into the valve chamber 4, is provided with an aperture through which projects the 65 valve stem 13 which carries at its end the conical valve 14 coöperating with the washer 10 to close the outlet passage. Surrounding the valve stem is a coil spring 15 which abuts at one end against the inside of the closure 70 5 and at its other end against the back of the conical valve 14. The valve stem 13 is fitted at its outer end with a handle 16 provided with an interrupted cylindrical extension comprising projections 17, as shown in 75 Fig. 4. The closure 5 is provided with a corresponding interrupted cylindrical extension comprising projections 18, as shown in Figs. 1 and 3. It will be obvious that when the projections 17 register with the recess between the projections 18 the valve will be 80 closed by means of the spring 15. When, however, the handle is pulled outwardly it can be turned to bring the projections 17 and 18 into engagement, thus holding the valve 85 open. When with the valve locked in open position it is desired to stop the flow of water a mere turning of the valve sufficient to bring the projections 17 into register with the recess between the projections 18 will 90 cause the valve to instantly close.

In operation when the valve opens the water passes down tubular extension 3 through valve opening and downwardly through the discharge 5' into a pail or other 95 receptacle as may be led away through a hose fitted over the lower end of discharge 5'. The spring 15 is strong enough to keep the valve normally closed in spite of the pressure of the water. By pulling outwardly on handle 16 the valve is opened and by release of handle 16 instantly closed. This instant control of the valve is of great utility in filling pails, etc., from the wash tub to empty the contents thereof, because 100 the flow of water can be shut off instantly when the pail is full; particularly because the outlet passage for the water is of comparatively large dimensions permitting a 105 large quantity of water to flow through in a 110

short time. If it is desired to leave the valve open the handle 16 is merely pulled back until the projections 17 escape the projections 18 and then slightly turned whereby 5 it is locked in open position. A quick turn of the handle 16 will then immediately cause the valve to become closed. The conical valve permits use of a large orifice through which the contents of the tub can 10 speedily escape.

I claim:

1. In a draining device of the class described a casing having an inlet passageway, an outlet passageway laterally offset therefrom and a third passageway connecting said inlet and outlet passageways and extending at right angles to each thereof, a valve seat in said third passageway with its axis parallel thereto, a closure in the side of 15 said outlet passageway and terminating at its outer end in an interrupted cylindrical member, a valve stem passing through said closure and having means to engage the interrupted portion of said cylindrical member whereby said stem may be quickly placed and held in open position with substantially 20 all sides of the valve plug exposed in the outlet passageway or released therefrom, a conical valve plug on said stem movable in 25 30 a path parallel to the direction of flow of

liquid past said valve seat, the inclination of the sides of said valve plug being such as to be washed clear of foreign matter by the outflowing liquid.

2. In a draining device of the class described a casing having an inlet passageway and an outlet passageway laterally offset from each other, an opening connecting said inlet and outlet passageways and extending at right angles to each thereof, a valve seat 35 in said opening, a valve stem, a valve plug on said stem for engagement against said seat, means for normally resiliently holding said valve plug against said seat, means for moving said valve plug away from said seat 40 in a direction parallel to the general direction of flow of liquid through said opening, said valve plug when in open position having substantially all sides exposed within the outlet passageway whereby the outflowing 45 liquid will wash past said plug and keep it clear of foreign matter.

In witness whereof I hereunto subscribe my name to this specification in the presence of two witnesses.

HOWARD F. SNYDER.
